COACH STRUCTURE

Everett W. Allen, Birmingham, Mich., assignor to
Yellow Truck & Coach Manufacturing Company, Pontiac, Mich., a corporation of Maine

Application July 9, 1940, Serial No. 344,563

6 Claims. (Cl. 296—44)

This invention relates to an improvement in public conveyances and more particularly to a body side wall structure having spaced roof supporting posts with observation openings therebetween to which windows are fitted. In the case of motor buses for city service having a central aisle and passenger seats placed against each side wall, space accommodation dictates the use of a main window which opens for ventilation by sliding upwardly between the belt rail and roof. The distance between the roof and belt rail determines what the vertical dimension of the sliding window may be and since the sliding window in closed position occupies a zone at the head level of seated passengers it becomes desirable to provide a secondary or standee window in the upper portion of the side wall and at approximately head level of passengers who may be standing in the aisle.

It is an object of the present invention to provide an improved window arrangement of the character referred to and which is of simple and inexpensive construction and whose operating mechanism is conveniently located for easy manipulation and ready accessibility for inspection and which furthermore presents a neat appearance.

Another object is to provide an arrangement of vertically spaced coach windows in which the window operating mechanism is firmly mounted on the rigid body posts in offset relation to the window so that in addition to secure attachment, better concealment and compactness are afforded with the operating handle out of the way of adjacent seated passengers, but within easy reach of both seated and standing passengers for window adjustments.

A further object is to provide a compact operating assembly and mounting to fit the restricted space available behind an interior trim panel or cover which cooperates with the body side wall to afford a window receiving well and is provided with an aperture in registry with the auxiliary or transom window for substantially unobstructed vision therethrough in all positions of the sliding window including its fully opened elevated position in tandem relation with the transom.

Additional objects and advantages will become apparent during the course of the following specification having reference to the accompanying drawing wherein Figure 1 is an elevation of a portion of a coach side wall as viewed from the interior and with parts broken away; Figure 2 is a fragmentary view with the elevated win-

dow in open position; and Figure 3 is a detail sectional view taken on line 3—3 of Figure 1.

Referring to the drawing, the belt rail is indicated at 1 with a pair of spaced side wall body posts 2—2 extending upwardly to the ceiling 3. A window sash assembly 4 of a vertical height of substantially one-half the distance between the belt rail 1 and lower edge of the ceiling 3 is provided to close the opening immediately above the belt rail and is slidably mounted at its opposite side edges in the body posts 2—2. Outside sheathing 5 extends across the posts and between the upper edge of the window opening and ceiling 3 and is provided at proper height above the window opening with a diamond-shaped opening in which is fitted and fixedly mounted the transom glass 6. Spaced inwardly from the outside panel 5 and cooperating therewith to form a window receiving well, is an interior trim panel 7 also provided with a diamond-shaped opening for registration with the area occupied by the transom window 6. Preferably the interior trim panel is removably or displaceably mounted as by means of a hinge connection along its upper edge so that it can be swung inwardly and upwardly for access to the interior of the well.

Outside the range of vision through the aligned transom openings and concealed behind the trim panel 7 is the operating mechanism for the sliding window assembly 4. For an out of the way location and a secure mounting the operating mechanism as an assembly is fastened on the mounting plate 8 and disposed to one side of the window well in line with an adjacent body post 2 to which it is securely bolted. The operating mechanism includes a gear train with the shaft of the driving gear 9 extending inwardly through the plate 8 and carrying an operating handle 10 in overhead relation to the seated passengers. The shaft of the large driven gear 11 carries a crank arm 12 connected by a link 13 to an intermediate portion of a lift lever 14. One end of the lift lever 14 is fulcrumed as at 15 on the mounting plate 8 and its opposite end extends laterally into the window well and carries a roller or slider 16 movable in a channeled guide rail 17 at the upper edge of the slidable window assembly 4. The elevating window 4 through the sliding connection between the channel 17 and lift lever 14 is raised or lowered upon rotation of the hand crank 10.

In elevating the window the guide channel 17 and lift lever 14 enter and traverse the transom window area bringing the sliding window into

tandem relation with the transom so that the window glass of the sliding sash assembly offers no interference to the range of vision through the transom. Because the fixed fulcrum 15 of the swinging lever 14 is located in substantial horizontal alignment with the major axis of the diamond-shaped transom opening, the lever and the window channel forming a part of the upper sash rail of the sliding assembly 4 are in substantial alignment or overlapping relation throughout their movement in the transom window area and thus combine to minimize transom obstruction. In all positions of the parts there is no unsightly mechanism in view and vision through the transom is open with little or no interference.

I claim:

1. In combination, a body side wall having a pair of spaced window openings with an intervening closed wall portion therebetween, a transom assembly fixedly mounted over one of the openings, a slideable sash assembly for closing the other opening and slideable into overlapping relation with the fixed transom assembly, and laterally mounted regulator mechanism having a lift lever projecting into the closed wall space between the window openings and out of alignment with the vision area of both windows when the sliding window is in its normally closed position for sliding engagement with the leading edge of the sliding window.

2. In an arrangement of the character described, a pair of vertically spaced window openings, a transom assembly fixed in the upper opening, a trim panel having an opening aligned with the transom assembly and affording a window well, a vertically slideable window assembly for closing the lower opening and movable upwardly from closed position and into said well in overlapping relation with the fixed transom, overhead operating mechanism offset laterally and outside the range of vision through both openings, and a lift lever operatively connecting said mechanism with the top of the slideable window and projecting inwardly into the well behind the panel and being arranged to swing from a normally concealed and closed window position across the line of vision through the transom when the window is slid toward and from closed position.

3. In combination, a vehicle body side wall having a window opening, an elevating window in the opening, an interior trim panel cooperating with the side wall to afford a window receiving well above the window opening, overhead operating mechanism offset to one side of the window opening and having a laterally extending

lift lever engaging the top of the window within the well, said trim panel and body wall having registering transom openings therein spaced above the window opening and so arranged that the window lift lever at its lower limit is wholly concealed by and between the trim panel and the wall and is partially exposed at the registering transom openings for a portion of its travel between opposite limits, and a window fixedly mounted in one of the transom openings.

4. In combination, an elevating window for an opening in a side wall, an interior trim panel cooperating with the wall to afford a window well above said opening and having a transom window opening in registry with a transom window in the side wall spaced above said side wall opening, and a window lift lever located in the well and positioned below and out of the range of vision through said transom window when the sliding window is closed.

5. In combination, a body side wall having a pair of window posts and a window opening between the posts, an interior trim panel located above the window opening in spaced parallel relation with a portion of the body side wall with which it cooperates to provide a window well and formed with a transom opening in registry with a side wall transom window, a window lift lever arranged at its lower limit to be concealed within the well below said transom opening, a fulcrum mounting for the lever on one of said posts in a horizontal plane substantially intersecting the transom opening and lever operating mechanism also mounted on the post and operable to cause the lever to enter and traverse the transom opening area.

6. In a passenger coach, a body side wall having a pair of vertically spaced window openings arranged at eye levels, respectively, of seated passengers and standees, a slideable window normally closing the lower opening and slideable upwardly across and in overlapping relation to the standee window opening, a laterally projecting lift lever engaging the lift rail at the top of the window and normally positioned beside the side wall in the space between the window openings and out of the range of vision through both openings, and means pivotally mounting the lever at a point horizontally between the top and bottom limits of the standee window openings and being so arranged that in the sliding of the window the lever traverses a portion of the standee window opening in substantial side by side alignment with the window lift rail for minimizing interference to vision through the standee window opening.

EVERETT W. ALLEN.
